CLAIM

The ornamental design for a smartwatch with electrocardiograph electrodes, as shown and described.

DESCRIPTION

1. Smartwatch with electrocardiograph electrodes
Figure 1.1 is a bottom front perspective view of a smartwatch with electrocardiograph electrodes;
Figure 1.2 is a front view thereof;
Figure 1.3 is a rear view thereof;
Figure 1.4 is a left side view thereof;
Figure 1.5 is a right side view thereof;
Figure 1.6 is a top view thereof;
Figure 1.7 is a bottom view thereof; and
Figure 1.8 is a top front perspective view thereof.
The broken lines shown in Figures 1.1-1.8 illustrate portions of the smartwatch with electrocardiograph electrodes that form no part of the claimed design. The dot-dash broken lines shown in Figure 1.1 and Figures 1.4-1.8 show the boundaries and form no part of the claimed design.
